UNITED STATES PATENT OFFICE.

EDWARD M. AYER, OF ROCKFORD, ILLINOIS.

MITER-BOX.

1,182,068.

Specification of Letters Patent.

Patented May 9, 1916.

Application filed February 28, 1913. Serial No. 751,307.

To all whom it may concern:

Be it known that I, EDWARD M. AYER, a citizen of the United States, residing at Rockford, in the county of Winnebago and State of Illinois, have invented certain new and useful Improvements in Miter-Boxes, of which the following is a specification.

This invention relates to miter boxes and has more particular reference to those having a saw-supporting lever pivotally mounted on a vertical axis on a frame to swing laterally with respect thereto to different working positions. Miter boxes of this general type have an elongated work-holding frame upon which a saw-supporting lever is pivotally mounted extending transversely thereof and with its upright saw guides located spaced from the front and rear of the frame.

One of the primary objects of this invention is to provide a saw-supporting and guiding means which can be readily detached from the frame without disturbing the pivotal mounting or the adjustment of the pilot arm.

Another object of my invention somewhat corollary to the foregoing is the provision of a saw-supporting lever having upright saw guides in fixed relation thereto, and of means pivotally mounted on the frame to swing laterally independently to various operative positions and to carry indexing and clamping means, whereby the saw-supporting means may be mounted on said pivoted means and be carried thereby to different working positions and be quickly and easily detached therefrom as a unit without disturbing the said pivoted means.

Another object of my invention is to provide novel means for adjusting the saw-supporting means laterally in a horizontal plane, and also for tilting the saw supporting and guiding means.

A further object is to provide a miter box of improved construction for the purpose of maintaining accuracy in its various movable parts and for permitting the miter box to be manufactured at a low cost. This is effected, more particularly, by forming substantially all of the parts of sheet metal drawn or stamped to the desired shape by dies, whereby all of the parts will be precisely identical.

In the accompanying drawings, Figure 1 is a plan view of the construction shown in my improved miter box. Fig. 2 is a front

elevation of Fig. 1. Fig. 3 is a vertical section taken on the line 3—3 of Fig. 1. Fig. 4 is a bottom view of Fig. 1. Fig. 5 is a detail section through a saw supporting post, taken on line 5—5 of Fig. 3. Fig. 6 is an enlarged sectional view of a portion of Fig. 3, showing the saw supporting lever locked to the base at a point intermediate two of the notches on the protractor segment. Fig. 7 is a detail section taken on the line 7—7 of Fig. 3, illustrating the horizontal adjustment of the saw supporting lever. Fig. 8 is a similar section on the line 8—8 of Fig. 3 showing the adjustment for tilting the saw frame to a vertical plane. Fig. 9 is a detail vertical section taken on line 9—9 of Fig. 6. Fig. 10 is a similar section taken on line 10—10 of Fig. 6.

The base 7 supported by legs 8 is of a sheet metal drawn construction having its center portion depressed forming a protractor scale 9, and supporting a back plate 10, the base 7 and plate 10 forming working faces, each of which has formed therein a plurality of elongated slots 11. An adjustable stop 12 is adapted to be locked to the base in any one of said slots desired, and because of the pivotal mounting of the stop and the position of the slots, the stop may be adjusted to a variety of positions to guide and hold various sized articles being worked upon. A bracing bar 13 formed on the under side of the base, has its central arcuate portion 14 disposed below and following the contour of said scale 9, and is provided at intervals with notches 15 corresponding with certain indications on the scale.

A pivot bolt 16 is mounted in the pivot support 17 and secures to said support 17 at its under side, the pilot lever 18 which extends to the front of base 7, contacting with the notched face of brace 14. A locking bar 19 of channel shaped construction is secured at its two ends by bolts 20 and screws 21 to the pilot lever 18, the bolts 20 being so adjusted as to hold the locking bar and pilot lever in smooth sliding contact with the faces of 9 and 14. The opening 22 in the locking bar enables the operator to see the readings of scale 9 at the point the saw cuts.

A saw supporting lever 23, U shaped in cross-section and having openings 24 and 25 in its horizontal face, is attached to pilot lever 18 by the set-screws 26 and 27, the set-screws extending through said openings, the

head of screw 26 engaging the lever 23, while the head of screw 27 engages the U section 28, which is located between the sides of lever 23, and is of less width than 5 said lever. These screws 26 and 27 clamp the lever 23 to the lever 18 against two sets of spaced pins 29 and adjusting screws 30 which are positioned to each side of the longitudinal center of lever 23, as is clearly 10 shown in Fig. 8. Saw supporting lever 23 has a longitudinally adjustable end 31 fitted to the outside of said lever and held in position thereon by set-screw 32.

To each end of lever 23 is secured an upper 15 right tubular saw-guide support 33 having a threaded end 34 extending through the lever and secured thereto by nut 35. Saw guides 36 are mounted on each of said supports and carry in their lower ends a friction dog 37 (Fig. 5) movable transversely in the guide and held yieldingly against the side of support 33 by a looped spring 38 having its end 39 held in an opening in the saw-guide. A detent 57 (Fig. 5) is formed 20 in 33 in which dog 37 is adapted to engage. The square upper face 37' of the dog prevents the saw-guide from being pulled beyond the detent, while the beveled under face 37² enables the dog to be withdrawn 25 from the detent upon downward pressure of the saw-guide. An adjustable stop 40 is carried to one side of each support 33.

Adjusting screws 41 (Fig. 7) are loose in the lever 23 and screwed in section 28 to 30 move said section transversely of the lever, thus moving the lever 23 transversely or horizontally with respect to the pilot lever 18, by the screw connection 27 between the lever 18 and section 28. The ends of screws 41 form a pivotal support for the hand lever catch 42 which is adapted to actuate a pin 43 upon which is mounted a dog 44 slideable in the sleeve 45 carried by lever 18, the dog being adapted to engage in the spaced 40 notches 15. A coiled spring 46 interposed between the lever 23 and lever catch 42 holds dog 44 into a notch as is shown in Fig. 3.

A clamping link 47 is pivotally suspended 50 from locking bar 19 by pin 48, and is connected at its lower end by pin 49 to clamp lever 50 which carries at one end the above mentioned pin 43. An adjustable screw stop 52 carried by pilot lever 18 forms a stop 55 against which the end 51 of lever 50 contacts, as shown in Fig. 6. The end of lever catch 42 which engages pin 43 is formed with open ends 53 (Fig. 6) which allow said lever catch to be withdrawn from said pin.

60 A depending spring catch 54 is carried by lever 23 and has an opening 55 in which the free end of lever catch 42 is adapted to engage, as shown in Fig. 6.

In the operation of the saw supporting lever 23, that is, in the swinging of said le-

ver from its pivotal support at 16, three elements, the locking bar 19, pilot lever 18 and saw supporting lever 23 are moved bodily carrying all the several actuatable elements therewith. With the parts positioned as 70 shown in Fig. 3, in order to swing lever 23, hand lever catch 42 is raised against the action of spring 46, drawing dog 44 from its locked engagement with the notched face of 14, thus allowing the said lever 23 to be 75 swung freely on its pivot. If it should be desired to lock said lever at a point intermediate two notches, the lever catch is drawn up higher until it is engaged in the opening 55 in catch 54, as shown in Fig. 6. 80 This action swings pin 43 still lower, which in turn raises end 51 to contact stop 52, the clamping lever 50 being pivoted at 49, whereby said clamping lever 50 with the stop 52 as its fulcrum, will draw the clamping link 47 down, thus tightening locking bar 19 and pilot lever 18 against the faces 9 and 14, and lock the saw supporting lever. To release the lever from this position, catch 54 is disengaged from the end of the lever catch. If the saw when it is positioned as in Fig. 1, does not cut at right angles to the face plate 10, the saw can be adjusted horizontally to remedy such defect by adjustment of the screws 41 to move the saw supporting lever as above described. To adjust the saw when it is tipped from its vertical plane, adjustment is made by the two screws 30, which pivot the lever 23 from the pins 29, there being enough play in supporting screws 26 and 27 to allow for such pivotal movement. 95

It will thus be obvious that I have provided a miter box which can be very quickly dismantled for packing and transportation purposes without affecting the pivotal mounting of the pilot arm. 100

In my improved miter-box, to remove the saw-guides and lever carrying same, only two screws 26 and 27 have to be loosened. When these screws are loosened, as will be seen from Fig. 4, the lever 23 may be moved longitudinally, until screw 26 is located in opening 24 and screw 27 is opposite opening 56 in lever catch 42, the lever catch being 115 drawn from pin 43 because of its open ends 53, thus releasing the said lever 23 carrying the lever catch 42 therewith, from the miter-box, the opening 25 allowing the clamping elements and dog to remain in their normal 120 position.

I claim as my invention—

1. In a miter box, the combination of a frame having an arcuate portion provided with a notched face, a pair of clamping bars pivoted co-axially on the frame on a vertical axis, one engaging the upper and the other the lower face of said arcuate frame portion, saw-supporting means connected with said bars to swing therewith, a 125

dog in connection with said bars and movable into and out of said notches, means for clamping said bars on the arcuate frame portion to lock the bars in connection therewith, and 5 manually operable means having a direct connection with said dog and bar-clamping means for operating the same.

2. In a miter box, the combination of a frame having an arcuate portion provided 10 with a notched face, a pair of clamping bars pivoted co-axially on the frame on a vertical axis, one engaging the upper and the other the lower face of said arcuate frame portion, a saw-supporting lever independent of and detachably connected to the lower clamping bar, a dog in connection with said bars movable into and out of said notches, means for clamping the bars on the arcuate portion of the frame and being carried 15 by the bars, and means carried by the saw-supporting lever for operating said dog and bar-clamping means and being automatically detachable therefrom when the saw-supporting lever is detached.

25 3. In a miter box, the combination of a frame having an arcuate portion formed with notches, means pivotally mounted on the frame on a vertical axis to swing laterally with respect thereto, a dog carried 30 by said pivoted means for engaging said notches, locking means carried by said pivoted means for locking the same in connection with the arcuate frame portion intermediate the notches thereof, saw-supporting means detachably connected to said pivoted means, and means carried by the saw-supporting means for operating the dog and locking means and being automatically 35 releasable therefrom when the saw-supporting means is detached.

40 4. In a miter box, the combination of a frame, a pair of pilot bars disposed respectively above and beneath said frame, rigidly connected together and permanently 45 mounted on the frame to swing about a vertical pivot, means carried by said bars for locking said bars in adjusted position on the frame, a member detachably connected to and carried by the lower pilot 50 bar, saw-guides mounted on the ends of said member, and means for actuating said locking means carried by said member and detachably connected to said locking means so as to be automatically disconnected 55 therefrom upon disassociation of said member from said pilot bars.

5. In a miter box, the combination of a frame, a pair of pilot bars, disposed respectively above and beneath said frame, rigidly connected together and permanently 60 mounted on the frame to swing about a vertical pivot, means for locking said bars in

adjusted position on the frame, a member detachably connected to and carried by the lower pilot bar, saw-guides mounted on the 65 ends of said member, and means for actuating said locking means carried by said member and detachably connected to said locking means so as to be automatically disconnected therefrom upon disassociation 70 of said member from said pilot bars.

6. In a miter box, the combination of a main frame, a pilot frame comprising an upper bar disposed above and a lower bar disposed beneath said main frame, said bars 75 being rigidly connected together and pivotally mounted on the main frame at their rear ends on a vertical axis, a member equipped at each end with a saw-guide disposed beneath the lower bar and detachably 80 connected to and carried by said bar whereby the saw-guides may be removed from and replaced on the frame without disturbing the relative relation of said guides or the pivotal mounting of the pilot bars, and 85 means for locking said pilot frame in adjusted position to the main frame.

7. In a miter box, the combination of a frame, a pair of pilot bars rigidly connected together and permanently mounted on the 90 frame to swing about a vertical pivot, means for locking said bars in adjusted position on the frame, a member extending beneath the frame and provided at each end with a saw-guide disposed respectively in 95 front and at the rear of said frame, means for detachably connecting said member to the lower pilot bar so that said member may be detached from the pilot bar without affecting the connection between the 100 pilot bar and the frame, and a manually operable device carried by said member for actuating said locking means.

8. In a miter box, the combination of a frame, a pair of pilot bars rigidly connected together and permanently mounted on said frame to swing about a vertical pivot, a member provided at each end with a rigidly attached saw-guide, means for detachably connecting said member to the 105 lower pilot bar, and adjusting means whereby said member may be adjusted laterally with respect to the pilot bar and also tilted with respect thereto to adjust both saw-guides simultaneously into desired position 110 with respect to the frame.

In testimony whereof I have hereunto set my hand in presence of two subscribing witnesses.

EDWARD M. AYER.
